UNITED STATES PATENT OFFICE.

CHARLES EDWARD ROCHAMBEAU, OF ST. JOSEPH, MISSOURI.

CAR-BRAKE.

1,052,967.

Specification of Letters Patent. Patented Feb. 11, 1913.

Application filed July 18, 1912. Serial No. 710,161.

To all whom it may concern:

Be it known that I, CHARLES E. ROCHAMBEAU, a citizen of the United States, and a resident of St. Joseph, in the county of Buchanan and State of Missouri, have invented a new and Improved Car-Brake, of which the following is a full, clear, and exact description.

This invention relates to railway rolling stock and has particular reference to an improved form of hand operated brake for freight cars or the like, whereby the trainman or brakeman will have better control of a car, especially in a switch yard where the cars are being handled in detached relation to the engine than has heretofore been possible with the ordinary forms of brakes.

Among the objects of this invention is to provide a brake or a set of brake mechanisms whereby a car may be under practically perfect control of the brakeman when operated either from the top of the car or adjacent either end thereof, the brake mechanisms being so disposed with respect to the car body or frame as to enable the brakeman to operate it freely by one hand while hanging upon the car with his feet and the other hand and irrespective of the condition of the load on the same or the adjacent car.

30 A further object is to provide brake mechanism whereby a car body may be loaded to the full capacity with respect to the necessary space allowed at the ends and which is not likely to be damaged or interfered with 35 in any way by an overhanging load either on the same or the adjacent car. On freight cars as usually constructed the brakeman is unable to see the yard and the various cars therein while he is in the act of controlling 40 the car being switched and many serious accidents arise because of such fact.

The foregoing objects are attained and the aforesaid difficulties are overcome by the mechanism to be hereinafter fully described 45 and claimed and shown in the drawings accompanying this specification in which like characters of reference indicate corresponding parts in all the views, and in which

50 Figure 1 is a side elevation of a brake operating device made in accordance with this invention, the face plate of the casing being removed; Fig. 2 is a transverse section on the line 2—2 of Fig. 1; and Figs. 3 and 4 are diagrammatic perspective views of 55 different types of freight cars showing sev-

eral different arrangements of my brake mechanism.

Referring particularly to the drawings, I show at 10 what may be regarded as a base plate adapted to be secured in a preferably 60 vertical plane at any convenient point on the end or side of a car and to which will be rigidly and permanently connected a housing or casing 11. The housing is shown as comprising a rear wall 12, a rim 13 and a 65 face plate or cover 14. A set of bolts 16 extend through the base plate 10 and through the casing securing the cover to the rim and the casing to the base plate.

Within the casing is a drum 17 having 70 portions 18 and 19 of different diameters connected preferably by a spiral groove 20. To the larger portion 18 is connected any suitable flexible draft connection shown as 75 a chain 21, the same being guided over said spiral groove and the smaller drum portion, and extending thence outward through the rim 13 and guided over any suitably arranged direction pulley 22. To the drum 17 is secured a gear wheel 23 adapted to be 80 driven by a pinion 24 mounted upon an arbor 25 adapted to be driven by a hand wheel 26. The arbor 25 and the axis 27 of the drum are parallel to each other and preferably journaled in the opposite walls of the 85 casing. By reason of the gear 23 and pinion 24 the chain 21 may be sufficiently tightened by operation of one hand to set the brakes, the chain being understood to be connected to the brake mechanism in any approved 90 manner. The length of the chain and the arrangement thereof upon the drum will be such that the first operation of the hand wheel will cause the slack in the chain to be taken up quickly on the larger portion 18 and when power is required for the setting 95 of the brakes the force will be applied through the smaller portion of the drum 19.

To lock the brake when set I prefer to use 100 a ratchet wheel 28 rigidly connected to the drum and gear wheel 23. Coöoperating with said ratchet wheel is a pawl 29 pivoted at 30 within the casing. The pawl is provided with a shiftable weight 31 mounted thereon in any convenient manner but 105 shown as being slidable along a guide 32 parallel to the pawl and connected to the opposite ends thereof. The weight 31 may be shifted by any convenient means and to this end I have shown connected thereto at 110

33 a rod 34 extending outwardly through the casing rim and terminating in a finger piece 35 whereby it may be moved to shift the weight from either end of the pawl to 5 the other. In the position indicated in full lines in Fig. 1, the weight will cause the pawl to engage the ratchet wheel and hence will prevent the reverse rotation thereof. When it is desired to release the brake, the 10 trainman will shift the weight to the other end of the pawl by pulling outward upon the rod 34 as indicated in dotted lines. The pawl will then be so counterbalanced as to swing free from the ratchet wheel.

15 In Fig. 3 is shown a box car A having a plurality of my brake operating devices connected thereto whereby the brakes may be set either from the top of the car or from a lower corner. By this arrangement a 20 brakeman on top of the car may have control thereof without climbing down or a brakeman adjacent the ground may control the car without being required to climb to the top of the car. It frequently happens 25 in shifting the cars in a yard that a brakeman does not have time to change his position with respect to the bottom or top of a car so as to control the speed of the car before it strikes the car to which it is to be 30 coupled.

In Fig. 4 is shown a flat car B adapted to be loaded to substantially its full length and hence the brake operating mechanism will be preferably placed below the plane 35 of the floor thereof as indicated on the side where it may be operated either from the ground or by hanging upon the side of the car where the brakeman will have a clear view of the yard and his proximity to any 40 cars that may be therein.

The several parts of the mechanism may be made of any suitable materials and the relative sizes and proportions thereof as well as the specific details of construction

may be varied to considerable extent without departing from the spirit of the invention. 45

Having thus described my invention, what I claim as new and desire to secure by Letters Patent is:—

50 1. The combination with a railway car, of a drum, a brake chain connected to the drum, means to rotate the drum to tighten the chain, and means to control the reverse rotation of the drum, said controlling means comprising a ratchet wheel and a pawl having a slidable weight thereon, substantially as set forth.

55 2. The combination with a railway car, of a drum, a brake chain connected to the drum, means to rotate the drum to tighten the chain, and means to control the reverse rotation of the drum, said controlling means comprising a ratchet wheel, a pawl pivoted intermediate its ends, and a weight slidable from one end of the pawl to the other, substantially as set forth.

60 3. In a railway brake operating mechanism, the combination of a chain, a drum to which the chain is connected, a gear wheel 70 and a ratchet wheel secured to the drum, a pinion meshing with said gear to rotate the same to tighten the chain, a pawl co-operating with said ratchet wheel, said pawl being pivoted intermediate its ends on a horizontal axis, a weight associated with the pawl and slidable from one end of the same to the other beyond said pivot, and a rod connected to the weight whereby it may be moved in either direction, substantially as 75 set forth.

80 In testimony whereof I have signed my name to this specification in the presence of two subscribing witnesses.

CHARLES EDWARD ROCHAMBEAU.
